FIG. 1 shows a general perspective view of the flotation vest with shark fin decoration. Side and chest straps and buckles are rendered in dashed lines; they form no part of the invention. Piping or edge binding at the edges of the vest is represented by stippled bands at the edges. Dashed lines in these stippled bands represent stitching of said binding.

FIG. 3 is a front view of the flotation vest with shark fin decoration.

FIG. 4 is a right-side view of the flotation vest with shark fin decoration.

FIG. 5 is a rear view of the floatation vest with shark fin decoration.

FIG. 6 is a top view of the floatation vest with shark fin decoration; and,

FIG. 7 is a bottom view of the floatation vest. The shark fin decoration is not visible in this view.

The broken lines on the piping or edge binding at the edges of the vest represent stitching; they form no part of the invention.
